UNITED STATES PATENT OFFICE.

PERCY WALTER DRUITT AND WILLIAM ROBERT GILPIN, OF LONDON, ENGLAND.

APPARATUS FOR COMPOSING AND CASTING TYPE.

1,161,635.

Specification of Letters Patent. Patented Nov. 23, 1915.

Application filed April 18, 1913. Serial No. 762,082.

To all whom it may concern:

Be it known that we, PERCY WALTER DRUITT and WILLIAM ROBERT GILPIN, both subjects of the King of Great Britain, both 5 residing in London, England, have jointly invented certain new and useful Improvements in Apparatus for Composing and Casting Type, of which the following is a specification.

10 This invention relates to apparatus for composing and casting type of the class which are provided with two or more magazines to accommodate a larger assortment of matrices which may be of one or of more than 15 one font or variety, and in which the separation of the matrices into groups according to their font or variety is effected by devices the operation of which is controlled by distinctive configurations given to the matrices 20 of the various classes. In one of these groups, or classes or varieties, the upper ears of the matrices are of the usual shape and these matrices may be designated normal matrices. The other group or groups of 25 matrices have one or both of their upper ears beveled according to the number and arrangement of the magazines, and these are designated modified matrices. Further all the matrices, both normal and modified, are 30 notched on one or both of their edges (according as there are two or more than two magazines) immediately under one or both of the upper ears.

The invention is embodied in one form in 35 Figures 1, 2 and 3 of the accompanying drawings which are respectively an end elevation, a transverse sectional elevation, and a front elevation with part broken away of the improved matrix distributing apparatus; Fig. 4 is a view similar to Fig. 2 showing modifications whereby the matrices may be divided into three groups; Fig. 5 is a similar view showing means for dividing into four groups; and Fig. 6 is an end elevation showing the mechanism for effecting the change from double to single magazine working.

The matrices 1, after casting is effected, are conveyed for redistribution in the magazines 2, 3 by the usual conveyer worms 4 along a distributor bar 5 in the known manner. Below the conveyer worms are disposed guide walls 6, 7 one at each side of

the distributor bar 5 and extending along the whole length thereof, which are designed 55 to guide the matrices into the entrance of the magazines, one of these guide walls, viz. 6, being for convenience formed in two parts. Upon each of these guide walls is pivotally mounted an oscillating latch or arresting 60 bar, 8, 9 respectively, extending the whole length of the magazine entrance, these latches being disposed at different levels and one, viz. 9, being designed to engage the matrices under the lower ears 10, while the 65 other viz. 8, is designed to engage under the upper ears 11.

Below the guide walls 6, 7 in the magazine entrance and extending the whole length thereof is pivotally mounted an oscillating 70 gate 12, which is laterally slotted at intervals to accommodate the divisional guide plates 13 forming the character compartments of the magazines. This oscillating gate 12 operates to divide the matrices into 75 two primary groups and when in either of its extreme positions it forms a continuation of one or other of the guide walls 6, 7 above referred to.

The latches 8, 9 and entrance gates 12 are 80 oscillated by means of suitable mechanism synchronously with the rotation of the conveyer worms so that they are brought into the appropriate positions for arresting and guiding the matrices at each revolution of 85 the conveyer worms. As the matrices 1 drop from the distributor bar 5 they fall vertically into the magazine entrance guides and are arrested in this position by the lower latch 9 engaging under their lower ears 10, 90 the upper latch 8 being at this phase withdrawn clear of the path of the falling matrices. During the momentary arrest of the matrices by the lower latch 9, the upper latch 8 is brought forward into the guide-way and the entrance gate 12 assumes one of its extreme positions. Under these conditions when the lower latch 9 is retracted the modified matrices (that is those matrices which have one or both of their upper ears 100 11 chamfered off) slide past the upper latch 8, drop down their respective channels and are guided by the entrance gate 12 into that magazine which is for the time being open to receive them, viz. as shown in Fig. 2, into 105 magazine 2. The normal matrices on the

other hand remain arrested by the upper latch 8 until upon the entrance gate 12 assuming its other limiting position and the upper latch being retracted, these matrices are allowed to drop down their respective channels into the second magazine 3.

The object of the notch or notches 14 on one or both edges of the matrices is to enable those matrices which have one or both of their upper ears chamfered off to be supported during their translational movements in the apparatus, a bead or beads engaging in the said notch or notches for this purpose. As the normal matrices traverse the same raceways as the modified matrices, it is necessary that they also should have a notch or notches in their edges to enable them to pass along the said bead or beads.

It will be understood that when it is required to divide the matrices into two groups only, the modified matrices need have only one of their upper ears, and that always the same one, beveled off as described and as illustrated in Fig. 2.

For separation into more than two groups, further distinctive configurations are introduced in the matrices of the several groups, and the separating process above described applied to one or both of the two primary groups into which the matrices are first divided. If the modified matrices have their right upper ears beveled off as shown at 11^a, the other primary group may be subdivided into two by forming the matrices of one of the sub-groups with their left upper ears beveled off as shown at 11^b (Figs. 4 and 5). This sub-group and the normal matrices, which in this case would form the second sub-group, are discharged from the first arresting and separating device 8, 9, 12 indifferently into a common guideway at the entrance of a double magazine 3, 3, which guideway is provided with a pair of oscillating latches 8^a, 9^a operating in conjunction with a second entrance gate 12^a to divide the group into two sub-groups in the manner above described and guide them into the two several parts of the magazine 3 which itself is a double magazine. Similarly the primary group of modified matrices may be divided into two sub-groups by having the left upper ears of some of these matrices beveled off, as well as their right upper ears, as indicated at 11^a, 11^b (Fig. 5), and providing another set of arresting latches 8^b, 9^b and oscillating entrance gate 12^b operating in the manner described, to separate the matrices of the two subgroups and direct them into separate magazines 2, 2.

When it is desired to deliver the matrices into one magazine only, the latches are held out of the guideway and the entrance gate or gates maintained in the position or positions which cause the matrices to be deflected into the required magazine.

The change from double to single magazine working is effected manually through suitable linkage actuated by a hand lever 15 mounted near the keyboard of the apparatus. The means whereby this is effected are shown in end elevation in Fig. 6.

To insure that the double distribution mechanism is operative when matrices are being taken from both magazines, the actuating mechanism is so coupled with a pedal-operated escapement mechanism (which may, for example, be of the character described in British Patent Specification No. 10832 of 1911) that any movement of this pedal 16 has the effect of bringing the double distribution mechanism into operation. Also, for single magazine working the position of the pedal 16 operating the escapement mechanism is arranged to determine which magazine is open for the reception of matrices.

The operation of mechanism such as above described for dividing the matrices into two groups and guiding them to their respective magazines may be conveniently effected as follows:—The two latches 8, 9 (Fig. 2) are normally urged inward against adjustable stops 17 so as to engage the matrices, by means of springs 18 situated at intervals along their lengths, each spring being located adjacent to a stop 17, this arrangement insuring that the latch projects an equal amount beyond the guide wall at every portion of its length. As shown in Fig. 2 the adjustable stops herein referred to are mounted in the latches, but obviously they may be alternatively mounted on the guide walls 6, 7. The latches are withdrawn from the matrix channel by means of levers 19, 20 operated by cams mounted on a spindle 21 which is geared with the distributor screws 4 so as to rotate synchronously with them. The lever or arm 19 is fast on the rock shaft or spindle of the latch 8, while the lever 20 which fulcrums on the spindle of the latch 8 extends beyond the fulcrum, the tail of the lever engaging an arm 20^a (Figs. 1 and 6) fast on the rock shaft or spindle of the latch 9. The gate 12 is oscillated in the direction to close one magazine, say the top magazine 2, by means of a cam rotating coaxially with the latch cams, motion being imparted to the gate through a cam lever 22 and link 23 connected with a lever 24 journaled on the axle 25 of the gate, the latter lever being spring-connected with a lever 26 adjacent to it, and fixed to the axle of the gate in such a manner that should the gate meet with any abnormal resistance to its movement the spring 27 will give and no damage will accrue to the mechanism. This spring 27 is also used in connection with the throw-out control mechanism to be described later. The two levers 24, 26 are adjusted and maintained in cor-

rect angular relationship by means of an adjustable stop 28. The gate 12 is returned to the position in which it closes the lower magazine 3 by means of a spring 29 attached to the cam lever.

5 The latch mechanism is rendered inoperative, and the gate moved to and retained in the position in which it closes the top magazine 2 by means of a vertically slideable control rod 30 which is arranged to be pulled downward by suitable mechanism, such as a Bowden wire mechanism 31 connected with a control gear within reach of the operator, and is returned by means of a spring 10 32. This control rod 30 on its downward movement operates, through an adjustable abutment 33 on its side and a lever 34 co-operating therewith, to raise the cam levers 19, 20 of the latches clear of their cams, a 15 pin 35 fixed in the end of the lever 34 engaging with the under sides of the ends of the cam levers 19, 20 of the latches. Simultaneously another adjustable abutment 36 on the control rod operates on the end of a 20 projection 37 of the gate cam lever 22 to draw it clear of its cam, and shift the gate 25 12 into the position in which it closes the top magazine 2.

To maintain the gate in the position in 30 which it closes the lower magazine, a bell crank is mounted on a fixed fulcrum 38 so that one arm 39 co-operates with a fixed abutment 40 on the lower end of the control rod 30, while the other arm 41 through 35 a suitably guided adjustable link 42 operates an arm 43 of the lever 26 which is fixed on the axle 25 of the gate 12. A second Bowden wire mechanism 44 is connected with the bell crank 39, 41 in such a manner 40 that a pull on the wire will operate to draw down the control rod 30, with the result described above, and also to shift the fixed lever 26 on the axle of the gate relatively to the other lever 24 journaled on the axle of 45 the gate, against the action of the spring 27 connecting them, thus moving the gate into the position in which it closes the lower magazine 3. The parts are returned to their operative position by the spring 32 on the 50 control rod described previously.

The lower ends of the Bowden wires 31, 44 are brought to a position adjacent to the keyboard, each wire being attached to a slide. These two slides 45, 46, which are 55 capable of horizontal movement, are located one above the other at a definite distance apart, and are suitably housed in a bracket 47 attached to the keyboard frame, the upper slide 46 being connected with the wire 44 operating to close the lower magazine 3, and the lower slide 45 being connected with the wire 31 operating to close the upper magazine 2. The movement of either of these two slides in a forward direction 60 (i. e. toward the operator) in order to op-

erate on the distributor mechanism, is effected by means of a drawbar 48 situated between them and carrying on its end adjacent to the slides two pawls 49, 50 mounted coaxially with one another, the other end of the drawbar being attached to the hand lever 15 pivotally mounted on the keyboard frame and adapted to move the drawbar in a horizontal plane, parallel to that of the slides. The drawbar 48 is connected at a 70 point between its two ends with the actuating lever 51 of the keyrod alternating frame by means of a link 52 in such manner that an upward movement of the link will bring that pawl which projects on the upper side of the drawbar, viz. pawl 50, into a position in which it will co-operate with a corresponding notch 53 in the upper slide 46. Similarly a downward movement of the link 52 will carry the lower pawl 49 75 into a position in which it will co-operate with a corresponding notch 54 in the lower slide 45. Thus it will be seen that a forward movement of the hand lever 15 when the link 52 is in its upper position, i. e. in 80 the position corresponding with that in which the keyrods are operating to discharge matrices from the top magazine, will draw the top slide forward, thus setting the gate to close the bottom magazine. A similar action would take place to close the top magazine with the keyrod alternating frame reversed as previously described.

In order that the slides 45, 46 may be held in their forward position, two spring- 95 impelled latches 55, 56 are provided one on either side of the drawbar 48, the upper one 56 being adapted to engage with a corresponding notch 57 in the edge of the drawbar when the latter is in its forward and upper position, and the lower one 55 to engage a corresponding notch 58 in the opposite edge of the drawbar when the latter is 100 in its forward and lower position.

Any movement of the keyrod alternating frame from one working position to the other, 110 will carry the corresponding pawl on the drawbar clear of its co-operating slide, thus allowing the control rod 30 under action of its spring 32 to move upward, thereby setting the double magazine distributing mechanism into operation. The same movement of the alternating frame will also carry the drawbar 48 clear of its engaging latch 55 or 56, and allow it to move rearward under the action of a spring 59 attached to the hand lever 15, into a position in which it would be ready to operate on the opposite slide with the next forward movement of the hand lever.

The Bowden wires, or other suitable linkage is adapted to operate through clutch 60 on a change speed mechanism in such a manner as to increase the speed of the distributor screws on the stoppage of the double 120 125 130

magazine distributor mechanism, in the manner described in British Patent Specification No. 10832 of 1911.

In machines of known kind having screw distributors and division plates, there is a cut out mechanism provided for stopping the machine when the matrices fail to drop clear of the screws, and are thus driven against a division plate. The controlling member of this mechanism is a rack bar which engages the edges of the springy tops of the division plates, and is displaced longitudinally under the circumstances above indicated, and thereby actuates mechanism operating to stop the distributing mechanism.

If it is preferred to fix the tops of the division plates 13 rigidly so as to preserve the accurate spacing of same, for which purpose they are held in slots in one or both of the guide walls, as indicated at 13^a (Fig. 2), this method of control cannot be adopted in such conditions. The lower distributor screw is therefore made the controlling member of the cut out mechanism, and is for this purpose arranged in a known manner to have a certain longitudinal freedom in its bearings, so that in the circumstances above indicated it will be displaced against the action of a spring 61, which serves under normal conditions to keep the screw in proper relationship with the other screws by forcing a shoulder 4^a on the spindle against its bearing 4^b.

The lower screw is connected with a known clutch actuating device through a slide 62 (Figs. 1 and 3), one end of which engages an annular groove 63 in the periphery of the screw, and the other end a bell crank 64, the lateral displacement of which by the slide operates to stop the distributing mechanism. This cut out device is also utilized in the present invention to stop the distributing mechanism should the gate 12 fail to reach either extreme position of its oscillatory movement. With this object a roller 65 on one arm of a cut out actuating lever 66 suitably fulcrumed as at 67, engages a cam 68 which revolves synchronously with the cam on the shaft 21 actuating the gate. The effective parts of this cam are two depressions 69 one of which comes over the roller 65 when the gate cam is in the position corresponding with either extreme position of the gate. Should the gate 12 be in its proper position the roller 65 is prevented from dropping into the corresponding depression in the cam 68 by means of a stop 70 on the fixed lever 26 of the gate engaging an appropriate lug 71 on the side of the cut out actuating lever 66, there being two such lugs, viz. 71 and 71^a, corresponding to the two extreme positions of the gate and fitted preferably with adjustable stops 72, 72^a. In this case nothing will happen and

the mechanism will continue running. Should, however, the gate 12 and consequently the stop 70 in the lever 26 fail to be in either extreme position when a depression 69 of the cut out cam 68 comes over the roller 65 of the cut out lever 66, the latter will be shifted by means of a spring 73, and a third lug 74 in the cut out lever will operate to displace the bell crank 64 above referred to, so stopping the mechanism as hereinbefore described.

Having thus described the said invention and the best means we know of carrying the same into practical effect, we claim:—

1. In apparatus for composing and casting type, a plurality of matrix magazines having a series of compartments, a distributor bar and conveyer worms common to said magazines, a pivotally-mounted gate extending the whole length of the entrances to the magazine compartments and controlling the entrances thereto, and means operating to give a periodic oscillation to said gate during each rotation of the conveyer worms.

2. In apparatus for composing and casting type, a plurality of matrix magazines, a distributor bar and rotating conveyer worms common to said magazines, a pivotally-mounted gate extending the whole length of and controlling the entrances to the magazines and means operating to oscillate the said gate periodically in timed relation with the rotation of the conveyer worms.

3. In apparatus for composing and casting type, a plurality of matrix magazines each comprising a series of character compartments, a distributor bar common thereto, oscillating latches adapted to arrest the matrices upon their release from the distributor bar, an oscillating gate coöperating with said latches, said gate extending the whole length of the series of character compartments and adapted to control all the entrances thereof, and means whereby the said gate and latches are oscillated in timed relation with each other.

4. In apparatus for composing and casting type, a plurality of groups of matrices each group having a distinctive configuration, a plurality of matrix magazines, one for each group of matrices, a distributor bar and rotating conveyer worms common to said magazines and matrices, a pair of oscillating latches one adapted to arrest all the matrices upon their release from the distributor bar and the other to arrest a group and allow the remainder to pass, an oscillating gate controlling the entrances to the matrix magazines, and means for projecting the latches alternately into the arresting positions and synchronously oscillating the gate, substantially as described.

5. In apparatus for composing and casting type, a plurality of matrix magazines, a distributor bar common thereto, a pair of

- oscillating latches located between the distributor bar and the magazines adapted to arrest the matrices upon their release from the distributor bar, an oscillating matrix 5 deflector coöperating with the said latches and extending the whole length of the distributor bar, means for projecting the latches alternately into the path of the matrices and withdrawing them therefrom, 10 and means for oscillating the gate in timed relation with the movement of the latches, substantially as described.
6. In apparatus for composing and casting type, a plurality of matrix magazines 15 arranged side by side in two parallel sets, a distributor bar common to the two sets, an oscillating gate extending the whole length of the distributor bar controlling the entrances to the two sets, a pair of oscillating latches coöperating with said gate and means for oscillating the latches and gate in timed relation with each other.
7. In apparatus for composing and casting type, a plurality of matrix magazines 25 grouped in pairs, and comprising each a number of compartments, a distributor bar and a guideway common to the pairs of magazines, a matrix arresting and separating device between the distributor bar and 30 guideway, an oscillating gate controlling the entrances to the compartments of each pair of magazines, a pair of oscillating latches coöperating with each gate and means for oscillating the gates and their 35 coöperating latches in timed relation with each other.
8. In apparatus for composing and casting type, a plurality of matrix magazines, a distributor bar common thereto, oscillating latches interposed between the said bar and the magazines, an oscillating gate controlling the entrances to the magazines and coöperating with said latches, means for oscillating the latches and gate in timed relation with each other and means controlled 40 by the operator for rendering the latches and gate inoperative, substantially as described.
9. In apparatus for composing and casting type, two sets of matrix magazines, a distributor bar and conveyer worms common thereto, latches and a deflector interposed between the said bar and magazines and normally oscillating in timed relation with 45 the rotation of the conveyer worms, means for arresting the oscillations of said latches and deflector, escapement operating mechanism controlling the issue of the matrices from the two sets of magazines, operating 55 mechanism therefor, and means controlled by the position of the escapement operating mechanism and operating to determine which set of magazines is open for the reception of matrices.
- 60 10. In apparatus for composing and cast- 65 ing type, two sets of matrix magazines, a distributor bar and conveyer worms common thereto, latches and a deflector inter- 70 with the rotation of the conveyer worms, means for arresting the oscillations of said latches and deflector, escapement operating mechanism controlling the issue of the matrices from the two sets of magazines, and 75 means insuring the operation of the latches and deflector consequent upon the actuation of the matrix escapement operating mechanism.
11. In apparatus for composing and cast- 80 ing type, a plurality of matrix magazines, oscillating latches, an oscillating gate or deflector coöperating therewith, cam levers actuating said latches and deflector, mechanism adapted to render the cam levers inoperative and shift the deflector into one of its extreme positions and means controlled by the operator for shifting said mechanism into the operative position.
12. In apparatus for composing and cast- 85 ing type, a plurality of matrix magazines, oscillating latches and an oscillating gate or deflector coöperating therewith, and mechanism adapted to oscillate the gate, comprising a cam lever, a crank loosely mounted on the gate axle and coupled with the cam lever, and a crank fast on the gate axle and spring-connected with the loose crank, substantially as described.
13. In apparatus for composing and cast- 90 ing type, a plurality of matrix magazines, oscillating latches and an oscillating gate or deflector coöperating therewith, mechanism operating to close the respective magazines, a pair of slides connected with said 95 mechanism, a draw bar adapted to coöperate alternately with either slide, a matrix escapement operating mechanism, and means actuated by said operating mechanism and operating to shift the draw bar into either 100 operative position, substantially as described.
14. In apparatus for composing and cast- 105 ing type, a plurality of matrix magazines, oscillating latches and an oscillating gate or deflector coöperating therewith, mechanism operating to close the respective magazines, a pair of slides connected with said mechanism, a draw bar adapted to coöperate alternately with either slide, a matrix escapement operating mechanism, means actuated by said operating mechanism and operating to shift the draw bar into either 110 operative position, and a pair of spring-urged latches adapted to retain the draw bar in the position into which it has been moved.
15. In apparatus for composing and cast- 115 ing type, a plurality of matrix magazines, a distributor bar and conveyer worms common thereto, latches and a deflector inter- 120
16. In apparatus for composing and cast- 125 ing type, a plurality of matrix magazines, a distributor bar and conveyer worms common thereto, latches and a deflector inter-

posed between the said bar and magazines and normally oscillating in timed relation with the rotation of the conveyer worms and a cut out mechanism operating to stop the distributing mechanism should the oscillating deflector fail to reach either extreme position of its movement, substantially as described.

In testimony whereof we have signed our names to this specification in the presence 10 of two subscribing witnesses.
